US0D1094311S

(12) **United States Design Patent** (10) **Patent No.:** **US D1,094,311 S**
(45) **Date of Patent:** **** Sep. 23, 2025**

(54) **WATERPROOF CONNECTOR**

(71) Applicant: **Shenzhen Jieruide Instrument Equipment Co., Ltd.**, Shenzhen (CN)

(72) Inventor: **Tianshu Yu**, Shenzhen (CN)

(73) Assignee: **Shenzhen Jieruide Instrument Equipment Co., Ltd.**, Shenzhen (CN)

(**) Term: **15 Years**

(21) Appl. No.: **29/926,270**

(22) Filed: **Jan. 30, 2024**

(51) **LOC (15) Cl.** **13-03**

(52) **U.S. Cl.**

(57) **CLAIM**

The ornamental design for a waterproof connector, as shown and described.

DESCRIPTION

FIG. 1 is a first perspective view of a waterproof connector showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the waterproof connector thereof; and,

FIG. 10 is another exploded view of the waterproof connector thereof.

(Continued)

The broken lines shown in the drawings depict portions of the waterproof connector that form no part of the claimed design.
